Patented Nov. 29, 1910.

FIG. 3

FIG. 2

FIG. 1

UNITED STATES PATENT OFFICE.

THOMAS F. PAYNE, OF PITTSBURG, PENNSYLVANIA.

VALVE.

976,908.

Specification of Letters Patent. Patented Nov. 29, 1910.

Application filed October 3, 1907. Serial No. 395,676.

To all whom it may concern:

Be it known that I, THOMAS F. PAYNE, of Pittsburgh, in the county of Allegheny and State of Pennsylvania, have invented a certain new and useful Improvement in Valves, of which the following is a full, clear, and exact description, reference being had to the accompanying drawing, forming part of this specification, in which—

Figure 1 is a vertical sectional view illustrating my invention and showing the valve in its closed position; Fig. 2 is a horizontal sectional view on the line 2—2 of Fig. 1; and Fig. 3 is a vertical sectional view showing the valve in its open position.

Like symbols of reference indicate like parts wherever they occur.

Heretofore in most self-closing valves for water-mains, wash-stands, &c., the pressure of the water in closing the valve has acted so rapidly as to cause an unpleasant and injurious jar and thumping when the valve strikes its seat.

The object of my invention is to provide a cushion which shall serve to deaden the force of the return of the valve at the end of its stroke and also to provide a self-closing valve of simpler and more durable construction than has heretofore been in use and which can be easily taken apart for repairing and cleaning.

In the drawing 2 represents the hollow casing having a spout 3, a flange seat 4, adapted to rest against the wall or shelf of the stand, and a threaded coupling extension 5, all of which parts may be formed in one piece. Inside of the casing 2 is the annular shoulder 6 which serves as a support for the valve seat and barrel. This valve seat and barrel are composed of a casting 7 which is adapted to be dropped into the interior of the casing 2, to rest on the shoulder 6, and to be held firmly in position by the screw cap 8 of the casing 2. At the lower end of the barrel 7 is the valve-seat 9 having a face against which the valve 10 is adapted to seat. In the barrel 7 above the valve-seat 9 is a double cylindrical chamber, the lower portion 11 of which has a greater diameter than the upper portion 11^a. The valve 10 may be formed of rubber or other like material adapted to seat itself against the valve-seat 9. On the valve-stem 13, above the valve 10, is a double cylindrical plug 12 having its lower portion 12 of such diameter as to fit within the cylindrical cavity 11, and

the upper portion 12^a of such diameter as to fit in the cylindrical cavity 11^a. Above the cavity 11^a is a partition 14 having a central opening for the passage of the valve stem 13. Secured to the upper portion of the valve-stem 13 is a nut 15, and between this nut and the partition 14 is the coiled spring 16, the force of which is exerted upwardly. Opening from the cavity 11^a, opposite the spout 3, is a passage 17 to permit of the free flow of water from the cavity. Bearing on the top of the valve-stem 13 is a V-shaped depressing cam 18 of the ordinary construction and having a handle 20. The barrel 7 is prevented from rotating in the casing 2 by the feather and spline 19. Opening from the upper or outer cavity 21 in which the spring 16 is located, is a small waste passage 22 which extends to a point opposite the upper portion of the mouth of the spout 3.

The operation is as follows: When it is desired to open the valve to permit of the flow of water therethrough, the handle 20 is given a half turn which depresses the valve-stem 13, the valve 10 and the plugs 12 and 12^a to the position shown in Fig. 3, the valve 10 being removed from its valve-seat and the plugs 12 and 12^a being lowered below the cavities 11 and 11^a respectively, thus forming a free channel for the flow of water from the water-pipe 5 to the spout 3. When the handle is released, the hydraulic force of the water unseats the depressing cam 18 and carries the valve stem 13 upwardly. Before, however, the valve 10 can strike against the valve-seat 9, the plugs 12 and 12^a enter the cavities 11 and 11^a, thus imprisoning water in the cavity 11 which serves as a cushion and prevents the valve from striking violently under the pressure of water against the valve-seat. The water thus imprisoned gradually leaks past the plug 12^a and permits the valve 10 to seat itself against the valve-seat 9. The purpose of the waste passage 22 is to permit the flow of water through the spout 3 to draw any water out of the cavity 21 that may have leaked therein by suction. As the upper portion of the barrel 7 fits tightly against the sleeve of the cap 8, no packing is necessary between the cap and the casing 2. As the valve-seat 9 is formed in the barrel 7, instead of in the casing 2, the valve may be lifted out of the casing with the barrel 7 when the cap 8 has been unscrewed from the casing.

The advantages of my invention which result from the devices which imprison the water and form a cushion, from the construction which enables the valve to be taken to pieces merely by the removal of the cap 8, and from the devices that enable leakage to be withdrawn by the suction of the water flowing through the valve, will be appreciated by those skilled in the art.

10 Having thus described my invention, what I claim and desire to secure by Letters Patent is—

15 In a self-closing valve, a casing having an interior annular flange, a removable barrel supported upon said flange and having a lower chamber constituting a fluid channel having passages of different diameters and

provided at its lower end with a valve-seat, and an upper chamber constituting a housing for a valve spring, a valve stem having 20 a valve and double plug arranged to enter said passages and form an intermediate closed annular pocket when the valve approaches the valve-seat, an intermediate wall separating said chambers and forming a seat 25 for said valve spring, and a port connecting said upper chamber with the valve outlet.

In testimony whereof, I have hereunto set my hand.

THOMAS F. PAYNE.
